SNAP SWITCH

Robert E. Moore, Baltimore, Md.

Application December 20, 1946, Serial No. 717,567

15 Claims.

(Cl. 200—67)

1

This invention relates to snap switch mechanisms and operating means therefor, and particularly to switches of the snap type operable to "on" and "off" positions by successive impulses in the same direction.

It is a general object of the present invention to provide novel and improved switch mechanisms and operating means therefor.

More particularly it is an object of the invention to provide in a snap switch mechanism a thrust lever adapted to be actuated always in the same direction for successive operations of the switch and including a movable pivot for the lever and means for limiting the travel of said lever.

More particularly it is an object of the invention to provide in a switch of the snap type a rocking yoke adapted to be maintained by an over-center spring in either of two positions and in which a portion of the rocking yoke remote from its axis of rocking forms a fulcrum and mounting for an operating or thrust lever adapted to receive a force in a direction approximately along its axis from suitable actuating means to move the yoke to activate the spring. Such thrust lever may or may not carry a movable contact forming a portion of the circuit of the switch.

One of the important features of the invention comprises a dual use of the over-center spring for actuating the yoke and contact and providing the return force for the operating member to insure it returning to its initial position after each operating thrust.

The switch of the present invention being particularly adapted for automatic operation, one of the features of the invention comprises a unique combination transformer and operating magnet for the actuating plate of a switch constructed in accordance with the present invention, whereby remote low voltage controls may be resorted to for operating the switch with the attendant advantages.

Other and further objects and features of the invention will be more apparent to those skilled in the art upon a consideration of the accompanying drawings and following specification wherein are disclosed several exemplary embodiments of the switch mechanism and the operating means therefor, it being understood that such variations, combinations and modifications of the same may be made as fall within the scope of the appended claims without departing from the spirit of the invention.

In said drawings:

Fig. 1 is a front elevation of a switch of the

2

single push-button style constructed in accordance with one embodiment of my invention and showing a single pole, double throw type;

Fig. 2 is a side elevation of the switch of Fig. 1 showing the relationship of the thrust lever and operating plate;

Fig. 3 is a view similar to Fig. 2 of a second embodiment of the switch having a different contact arrangement and including means for providing operating plate return from the main spring;

Fig. 4 is a section taken on line 4—4 of Fig. 3;

Fig. 5 is a top plan view of the switch of Fig. 3;

Fig. 6 is an illustration of a further arrangement of thrust lever having unique limiting stops;

Fig. 7 is a still further modification of thrust lever and cooperating operating plate and contact making stops; and

Fig. 8 is a schematic showing of combined switch operating magnet and transformer.

The present switches were developed in an effort to provide satisfactory forms of such switches which reverse their contact positions once each time the actuating lever or button is depressed and released. Most such mechanisms have inherently low mechanical efficiencies and hence require too great an effort in their operation to warrant the use of low voltage actuators where desired. The mechanism suggested for use herein as suitable embodiments of the present invention have mechanical efficiencies above fifty percent. This efficiency may be defined as the ratio of the energy required for one operation of the switch to the basic energy required to separate the contacts to the dead-center toggle position.

Referring first to Figs. 1 and 2 for a simple form of the invention, it will be seen that the switch comprises a suitably stamped and bent sheet metal frame 10 having a side wall 11, a back wall 12, a skeleton front wall 13 and a top flange 14. Mounted on the frame are insulating blocks 16 and 17 to which are suitably attached contact tabs 18 and 19 carrying respectively the facing contact buttons 20, 21 thereon, spaced apart as shown in Fig. 1. Movable contacts 22 carried by a bent flange on the lower end of sheet metal thrust lever 23 are adapted to alternately engage the stationary contacts and receive their current through the frame of the switch, or if insulated from the thrust lever, are connected by a flexible pig tail to a suitable stationary terminal.

55 The snap action of the switch is accomplished by means of a rockable U-shaped yoke 25 pref-

erably formed of rigid wire having the out-turned fulcrum ends 26 pivoted respectively in notches 28 and 29 in the tab 30 in the front wall 13 and in the back wall 12. The wide bottom of the yoke has its center bent upwardly as at 30 to provide a stud for the helical expansion spring 31 the opposite end of which fits over stud 32 on arm 33 bent horizontal from the wall 11 and positioned vertically beneath the axis of pivot of the yoke. Under these conditions the spring becomes an over-center spring and will force and hold the yoke to either side of a plane passing through its axis pivot and the stud 32, depending on which side of the center it is initially placed.

To start the throw of the yoke by moving it beyond the dead-center position from whatever position of rest it may be in, the thrust lever 23 is fulcrumed on the bottom reach of the yoke as at 35 or on any suitable fulcrum remote from the yoke rocking axis. To insure the main portion of the thrust lever remaining parallel to the sides of the frame and of the yoke, it has an integral arm 36 extending parallel to reach 35 and carrying a tab 37, the latter being also fulcrumed on the yoke as clearly seen in Fig. 2. Rotation of the thrust lever in respect to the yoke may be limited by various means. As shown in Figs. 1 and 2 spaced stop arms 39 and 40, bent up from the sides of the thrust lever span one of the side wires of the yoke against which they alternatively engage, as seen in Fig. 1. Thus the contacts on the lower arm of the lever serve to limit the throw of the yoke.

For movement of the thrust lever substantially in line of its axis, resort is had to an operating plate 42 having a pair of spaced apertures 43 therein each fitting over a narrow tongue 44 extending upwardly from the back wall 12. The body of the operating plate rests against the edge of frame wall 12 between the tongues. A narrow arm 46 extends from the plate beyond this fulcrum and is bent to provide an anchor for one end of the helical tension spring 47, the other end of which is anchored from arm 48 struck out from the back wall 12. This insures the movement of the operating plate in a clockwise direction as viewed from Fig. 2, such movement being limited by engagement of the far edge of the plate with the end face of a push button 50 working through an aperture in the top wall 14 of the frame.

In operation the switch contacts change position once for each time that the button 50 is pressed and released. Upon such pressure the plate 42 moves downwardly in a counterclockwise direction and engages the upper end of thrust lever 23, forcing the latter downwardly and swinging the yoke in a clockwise direction, as viewed in Fig. 1, until the over-center spring takes control and moves the yoke to its opposite position as determined by contact and stop on the lever, which partakes of a partial counterclockwise rotation.

An important feature of the arrangement is the sliding and rocking motions given to the movable contacts in respect to stationary contacts at the time of initiating movement of the switch parts, thus insuring that the contacts are free to separate when the spring takes control. As the spring swings the yoke over, contact 22 makes engagement with contact 20 and further movement of the yoke rotates the lever 23 in a counterclockwise direction as seen in Fig. 1 until stop 40 comes into engagement with the side arm of

the yoke limiting the movement so that the upper end of the thrust lever remains beneath the operating plate 42 ready for the next operation of the latter. The shoulder 51 on the side wall 5 of the frame limits the downward movement of the operating plate 42. Final movement of the top of 23 does not occur until 42 is released but the desired contacts are already in engagement and only roll slightly.

10 The switch of Figs. 1 and 2 is not necessarily limited to the contact arrangement shown, for obviously various types of contacts may be mounted in other positions as long as at least one of them is carried by some portion of the 15 switch which alternatively assumes one of two positions in which it remains until the next actuation of the push button.

10 The switch of Figs. 3, 4 and 5 makes use of the basic features already described and the frame 20 construction need not be referred to more specifically except in so far as it differs from that already described. In this arrangement yoke 25' has its right hand journal 26' considerably longer than in the first embodiment and the fulcrum 25 for the operating plate 42' is so positioned that the plane of the operating plate intersects this portion 26' where it is cut away to prevent interference therewith, as shown at 60. The portion 61 beyond this cutout engages beneath the under surface of the portion 26' as clearly seen in Fig. 3, so that it holds the plate cocked up in the position illustrated against the under face of push button 50'. When plate 42' is depressed, portion 61 engages beneath 26' and lifts the whole 30 side of the yoke sufficiently to compress the over-center spring 31', which thereby acts not only for its designated purpose but to maintain and return the operating lever to its upper position, thus dispensing with the operating plate spring 35 40 41 of Fig. 1.

45 In the second embodiment of the switch the over-center spring 31' bears against the bottom reach of the yoke, but its upper end, instead of engaging a stationary stud on the frame, is mounted over a nub portion 62 in the inner horizontal arm 61 of a wire stirrup having a substantially vertical arm 64 offset therefrom by portion 65. Arm 64 merges into a horizontal portion 66 at the bottom which bears in a pair of 50 indentations 67 in spaced cross strips 68 stamped out from the bottom wall 69 of the frame. The outer horizontal arm 63 of the stirrup extends parallel to the axis of oscillation of the yoke and forms a bridging member adapted to engage the 55 spaced contact springs 70 mounted on an insulating block 71 carried by arm 72 of the frame. It thus bridges them to close the circuit. These contacts likewise act as a stop limiting the swinging of the stirrup under the action of spring 31' 60 to the position shown in Fig. 4. Movement of stirrup 64 in the opposite direction when the yoke is swung over is limited by stop 73.

65 Thrust lever 23', which is preferably pivoted to the bottom element of the yoke, as in the earlier embodiment, carries stop lugs 39' and 40' to engage with the yoke side element, but since there are no contacts to limit the movement of the lower end of this lever it is provided with spaced tines 75 and 76 straddling the bottom horizontal 70 pivot portion 66 of the stirrup, which acts as a stop for one or the other of them, depending on the position of the thrust lever and thus limits the swing of the yoke.

In the operation of this embodiment an additional movable element is made use of to carry

the movable contact, and it is actuated by the opposite end of the over-center spring. By this construction the contacts are completely removed from any possible manipulation by the operator which might cause arcing and are solely under control of the spring.

In Fig. 6 is illustrated a further embodiment of the thrust lever 23² capable of use with either type of switch shown in the first two embodiments. It is shown as fulcrumed on the yoke element of 25² as in the previous embodiments and is provided with upper and lower lateral stop arrangements to limit its movement, one of which may be replaced by contacts. Thus the lower end is narrowed to a tongue 100 working in slot 101 in the bottom wall of the frame, the ends of which slot limit lateral movement of the lever. The upper end is likewise provided with a tongue 106 working in slot 107 in the operating plate. The shoulders 102 or 103 on the lever are selectively engaged by the lower surfaces 104 or 105 of the operating plate to impart thrust to the lever, while tongue 106 working in the slot selectively engages the ends of the slot to limit lateral movement of the top portion of the thrust lever. With this arrangement no stops are needed between the yoke and lever to limit relative movement therebetween.

In Fig. 7 the thrust lever 23³ is arranged, at the bottom, the same as the one in Fig. 6. Top lateral stops are composed, at one side, of engaging contacts 109 and 110 and the side of the lever and abutment 112 stamped from the wall of the frame on the other. In this construction the operating plate 42³ is provided with companion indentations 115 and 116 above the respective stationary positions of the tip 117 of lever 23³ serving to prevent lateral travel of the upper end of the thrust lever when it is being pushed downwardly before the spring takes over, so that the contacts will not bind excessively but will be slid to insure their breaking loose and to keep them wiped clean.

Manifold economies may be effected in the wiring of buildings and houses by arranging control switches adjacent the apparatus which they control or at some point in the wiring system not requiring any excess working-voltage conductors and operating them remotely through low voltage circuits. This eliminates the need for large quantities of insulated and protected cable or conduit running to switches at distant points. The low voltage conductors can be relatively small in size and have only nominal insulation. Conduit boxes would not be required for simple momentary contact push button switches in control of these low voltage conductors.

Fig. 8 shows a simple magnetic means for actuating the operating plate 42 of any of the switches hereto described. Low voltage for the operating circuit is developed by a transformer 200, the magnetic circuit of which includes a closed core 201 and an L-shaped extension portion 202 and 203, on the upper free end of which the fulcrum for the combined plate and armature 42 is provided. A high voltage winding 204 passes through the window of the core 201 and is energized from the high voltage power source continuously. A low voltage winding 205 likewise passes through the window and may be wound on the same or another leg of the core, and is connected to a control switch 206 by low voltage conductors 207.

In operation, with the circuit of 205 open, the magnetizing flux in the core is insufficient to cre-

ate enough flux in the air gap at 208 to attract the operating plate 42. When, however, the circuit of winding 205 is closed, the voltage induced in this winding causes a current flow therein producing a magneto-motive-force opposing that generated by winding 204, causing the current in this latter coil to increase to maintain the flux at its equilibrium value. The increased flux in the core is partially shunted to the air gap resulting in sufficient attraction to draw down plate 42 and operate the switch (not shown) which may be mounted in the arms of the core L. Release of the push button 206 opens the low voltage winding circuit and the core flux drops sufficiently for the armature attraction to be overcome by the spring 47 whereby plate 42 is lifted and made ready for the next operation of the switch. The amount of current used by primary winding 204 is inconsequential and usually insufficient to operate the meter.

I claim:

1. In a switch of the type described, in combination, a frame, an actuator adapted to be moved and returned for each opening and for each closing of the switch, a yoke mounted for rocking on said frame, an over-center spring having one end bearing on said yoke and the opposite end supported independently of said actuator, a thrust lever journaled on a portion of the yoke remote from its axis of rocking and extending partially between the yoke arms, said lever being arranged for transmitting thrust from the actuator to move the yoke from either position of rest sufficiently to start the spring over-center and to then cross the axis of rocking of the yoke when the actuator is returned, a stationary contact carried by said frame, and a second contact carried on one of the movable parts of the switch.

2. In a switch of the type described, in combination, a frame, a yoke mounted for rocking on said frame, an over-center spring having one end bearing on said yoke, a thrust lever journaled on a portion of the yoke remote from its axis of rocking and extending partially between the yoke arms, said lever being arranged for transmitting thrust to initially move the yoke from either position of rest sufficiently to start the spring over-center, a stationary contact carried by said frame, a second contact carried on one of the movable parts of the switch, cooperating means on and limiting relative rotation of the yoke and lever and means forming a stop for said lever opposite its journal from the said cooperating means.

3. In a switch of the type described, in combination, a frame, a yoke mounted for rocking on said frame, an over-center spring having one end bearing on said yoke, a thrust lever journaled on a portion of the yoke remote from its axis of rocking and having a portion extending between the yoke arms and beyond the axis, a plate rockably mounted on said frame, said lever being arranged for transmitting thrust from said plate to initially move the yoke from either position of rest sufficiently to start the spring over-center, a stationary contact carried by said frame, a second contact carried on one of the movable parts of the switch, means limiting relative rotation of the yoke and lever, and means limiting transverse movement of the lever.

4. A snap switch assembly including a frame structure, a yoke mounted for rocking on said frame about an axis, an over-center spring arranged between the frame and yoke to control the position of the latter, a thrust lever jour-

nalled on said yoke about a second axis parallel to and remote from said first axis, said lever having a portion extending in the general direction of the first axis, means limiting relative rotation of the lever and yoke, means including said spring to always position said lever portion to the same side of a plane through the said first axis of the yoke bisecting its angle of throw as the yoke is positioned, an operating plate adapted to be moved generally in the axial direction of said lever to impart a thrust to the said portion of the same and contacts fixed respectively to the frame and a movable part of the switch assembly.

5. The snap switch assembly as defined in claim 4 in which the operating plate is fulcrumed to the frame structure for movement about an axis at right angles to that of the yoke.

6. The snap switch assembly as defined in claim 4 in which the operating plate is fulcrumed to the frame and means associating said plate and yoke whereby said spring retracts the plate upon release after actuating said lever.

7. A snap switch including a frame, a yoke pivoted for swinging in said frame about an axis, a stirrup pivoted for swinging in said frame about an axis parallel to and remote from said first axis, an over-center spring compressed between parts of said yoke and stirrup each remote from its axis, stops limiting movement of said stirrup, one of said stops comprising a stationary contact, a thrust lever pivoted to said yoke remote from the axis of the latter, a portion of the lever extending generally toward the yoke axis, and means including the spring causing the said portion to assume a position divergent to the plane of said yoke and on the opposite side thereof from the spring.

8. The switch as defined in claim 7 in which said last mentioned means also include stops limiting relative motion of the yoke and lever.

9. The switch as defined in claim 7 in which said last mentioned means also include stops limiting relative motion of the yoke and lever and stops limiting movement of the yoke in respect to the frame.

10. A snap switch mechanism including a frame, a yoke pivoted for swinging in said frame, an over-center spring effective between the frame and yoke, a lever journalled intermediate its ends to a portion of the yoke remote from its pivots, spaced means on said frame to be alternatively engaged by one end of said lever to limit its transverse motion, means on said frame to be alternatively engaged by the other end of the lever to limit its transverse movement, and an actuating plate adapted to impart thrust to the last mentioned end of the lever in either of its stopped positions.

11. A snap switch mechanism as defined in claim 10 in which the last mentioned lever end and the actuating plate are provided with interfitting means at the said position.

12. The switch as claimed in claim 1 in which a stirrup fulcrumed to the frame remote from the yoke axis supports the opposite ends of the spring, said movable contact being mounted on said stirrup.

13. A snap switch including a frame, a yoke

5 pivoted for swinging in said frame about an axis, a stirrup pivoted for swinging in said frame about an axis parallel to and remote from said first axis, an over-center spring compressed between parts of said yoke and stirrup each remote from its axis, stops limiting movement of said stirrup, one of said stops comprising a stationary contact, a thrust lever pivoted to said yoke remote from the axis of the latter, a portion of the lever extending generally toward the yoke axis, means including the spring causing the said portion to assume a position divergent to the plane of said yoke and on the opposite side thereof from the spring, said stirrup comprising the other contact and means limiting the relative rotational movement of lever and yoke.

14. A snap switch mechanism including a frame, a yoke pivoted for swinging in said frame, an over-center spring effective between the frame and yoke, a lever journalled intermediate its ends to a portion of the yoke remote from its pivots, spaced means on said frame to be alternatively engaged by one end of said lever to limit its transverse motion, spaced means on the opposite end of the lever to alternatively engage the yoke to limit relative movement of the lever thereto, an actuating plate adapted to impart thrust to the last mentioned end of the lever in either of its stopped positions, a contact carried by and insulated from the frame and an engaging contact movable relative thereto under the action of said yoke.

15. In a switch of the type described, in combination, a stationary frame, a movable member mounted for rocking on said frame about an axis, a movable thrust lever pivoted on a portion of said rocking member remote from its axis of rocking, an over-center spring bearing on one of the movable parts at a point remote from the said axis, said thrust lever being arranged for transmitting thrust for compressing the spring to initially move the rocking member from either position of rest sufficiently to start the spring over center, a stirrup pivoted on said frame on an axis parallel to and remote from the axis of rocking of said member, the opposite end of said spring being mounted on the stirrup remote from its axis, a contact carried by a part of the stirrup, and a cooperating contact carried by said frame.
